DESIGN FOR A RING

Nathan Heyman, New York, N. Y., assignor to
Oscar Heyman & Brothers, Inc., New York,
N. Y., a corporation of New York

Application September 6, 1939, Serial No. 87,070

Term of patent 14 years

To all whom it may concern:

Be it known that I, Nathan Heyman, a citizen of the United States, residing at 125 E. 84th St., New York city, in the county of New York and State of New York, have invented a new, original, and ornamental Design for a Ring, of which the following is a specification, reference being had to the accompanying drawing, forming part thereof.

Both sides of the ring present the same appearance as the sides shown in the drawing.

The figure is a perspective view of a ring showing my new design.

I claim:

The ornamental design for a ring, substantially as shown and described.

NATHAN HEYMAN.
